MITER FORMING DEVICE FOR CURTAINS
AND THE LIKE

David H. Rosenberg, New York, N. Y.

Application November 17, 1937, Serial No. 174,967

8 Claims. (Cl. 112—137)

This invention relates to miter forming devices for curtains and other textile fabric articles while they are being sewn, and has for one of its objects the provision of a device referred to comprising a border, frame, or band forming member and means associated therewith for forming a miter joint at the corners of such articles.

Another object of the invention is the provision of such a device including a miter forming or shaping member or guide and pivotally mounted means for folding the textile material about the miter forming or shaping guide.

A further object of the invention is the provision of a device of this character in which the miter joint folding means may be slid out of contact with the joint after same has been formed without in any way disturbing the said joint.

A still further object of the invention is the provision of such a device which will turn the raw edges of the band or border material inwardly to form a neat or clean edge where they are sewn to the curtain or other textile article.

Yet another object of the invention is the provision of a miter forming device in which the miter forming or shaping shell or gage may be shifted into and out of operative position.

Still another object of the invention is the provision of such a device in which the border or frame forming guide or members may be pivotally or hingedly connected to each other for convenience in initially inserting the border forming fabric.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

In the accompanying drawings:

Figure 1 is a top plan view of one form of my improved miter forming device, showing the miter

forming shell in the normal ineffective position in full lines, and also showing same in dot and dash lines in effective miter forming position;

Figure 2 is an inverted end view of the device looking from the top of Figure 1;

Figure 3 is a perspective view of same partly broken away;

Figure 4 is a cross sectional view taken on line 4—4; Figure 1;

Figure 5 is a fragmental view in side elevation showing the miter folding or forming fingers within the interior of the miter forming shell as shown in dot and dash lines Figure 1;

Figure 6 is a cross sectional view taken on line 6—6 Figure 1 showing the fabric folded about 15° the miter forming shell;

Figure 7 is a plan view of the miter forming shell;

Figure 8 is a side view thereof looking from the right of Figure 7;

Figure 9 is a top plan view of a modified form of my invention;

Figure 10 is a side view thereof looking from the right of Figure 9 and;

Figure 11 is an end view thereof looking from the bottom of Figure 9.

Referring now to Figures 1 to 8 of the drawings in detail 15 indicates the border forming shell and guide of my improved miter forming device, the said shell comprising an outer U shaped wall 16 and an inner U shaped wall 17 preferably bent therefrom, the said inner wall being spaced from the outer wall to form a U shaped channel 18 into which the band or border forming material 19 may be threaded or inserted. At each end of the channel there is provided an L shaped strip or member 20 for bending the raw edges of the band forming material inwardly to form turned over edges 21 where the border is secured or sewn to the curtain material 22 (see Fig. 4).

Slidably yet frictionally mounted in guideways 23 is a shell 24 which is substantially U shaped in cross section and the rear end thereof being cut at an angle to form acute angular folding edges 25. A handle 26 is secured to the upper end of the shell 24 by which it may be slid to and fro in the shell 15 between stops 27 and 28. The handle 26 protrudes outwardly from the shell 15 through an elongated slot 29 at the right hand side of the device, the said slot being formed between guideways 23.

At the left of the device and extending longitudinally thereof there is slidably mounted in a pair of spaced apart bearings 30 a rod 31 which is preferably rectangular in cross section. At the

55

rear end of the rod 31 there is pivotally yet somewhat frictionally mounted a bifurcated block 32, the said mounting being provided by means of a pin 33 passing through the said block and a boss 34 forming the lower end of the rod. The block 32 is provided with a handle 35 by which it may be rotated or swung about its pivot 33 to bring the miter folding fingers or pins 36 into the interior of the miter shaping shell 24 to bend the border material 19 inwardly about the edges 25 and against the base 24^a to form the miter joint 40 (see Fig. 1). If desirable the base 24^a may be slotted as at 41 to permit the border forming material to be fully pressed rearwardly 15 against the base 24^a. A pair of stops or collars 42 and 43 are provided on the rod 31, the collar 43 being normally drawn against the rear bearing lug 39 by means of a spring 44 one end of which may be secured to a pin 45 carried by the 20 front lug or bearing 30 and the opposite end of the said spring may be secured to a pin 46 carried by the collar 43 which is secured to the rod 31. The entire device may be adjustably mounted on the sewing machine by means of 25 screws 47 passing through elongated slots 48 in a base or extension 49 secured to the lower wall portion of the outer wall 16.

In practice when sewing the border 19 to the curtain material 22, the edge 50 of the said curtain is inserted between the upper and lower layers of the said band and the curtain and band are then sewn together by a row of stitches 51 from the lower edge 52 of the curtain to the upper edge 53 of the said curtain. When in this 30 position the bar 54 carrying the presser foot 55 is lifted up with the needle 56 penetrating the curtain and border material, and the miter shaping shell 24 is then moved to assume the dot and dash position shown in Figure 1. With the miter shell in its adjusted position, the block 32 is 35 swung about its pivot 33 to bring the fingers 36 into their upper or dot and dash position. During the swinging of the said block and fingers the border material is folded inwardly of the miter shell and bent over the angular edges 25 to form 40 the joint 40. The rod 31 is then pushed rearwardly of the machine or downwardly as indicated by the arrow 59 Figure 1 against the tension of the spring 44 until the fingers 36 are fully 45 withdrawn from the miter joint. The block 32 is then swung to its normal ineffective position and the spring 44 is then permitted to return the rod to its normal inoperative position. If desired the spring 44 may be omitted and the rod 50 may be manually moved forwardly and rearwardly. It will be understood that during the formation of the joint 40 the curtain 22 is moved until the horizontal edge 52 assumes the vertical 55 position indicated in dot and dash lines at right of Figure 1. The edge 53 also assumes a vertical position and it is then inserted and sewn to the border 19 along its entire length after which the mitering operation is repeated and so on until the entire curtain is completed.

60 It is to be understood that the curtain material does not pass through the shell, but the leading end edge thereof is inserted between the upper and lower layers of the folded band somewhat beyond the rear end of the outer shell, and as 65 the sewing progresses the side edge of the curtain material is manually fed or inserted between the band layers by the operator.

In Figures 9 to 11 I have shown a modified form of my invention wherein the band or border forming shell 60 comprises a lower section 61

and an upper section 62, the said sections being hingedly connected at 63, the said hinged joint being provided so that the device may be opened up for the insertion or threading of the band or border forming material. The lower section 61 5 may be provided with bearings 64 in which the rod 31^a is slidably mounted, the miter forming fingers 36 being pivotally mounted at 33 as in the form above described. The miter shaping or forming guide 24^b is in the present instance stationary instead of slidable and is formed by means of an upper wall or extension 64^a bent inwardly from the lower wall 61 and by a similar extension 65 bent from the upper wall 62. The said extensions are spaced from each other and from 10 their respective sections to form a channel 66 in all respects similar to the channel 18. L shaped strips 67 are provided in the right hand of the channel 66 to provide means for folding over the edges of the band forming material where it 15 is sewn to the curtain.

The form of my invention just described is precisely the same as that shown in Figures 1 to 8 with the exception that the shell sections are hingedly connected to each other and the 20 miter forming guide is stationary instead of movable.

To form the miter joint, the fingers 36 are 25 operated to fold the fabric about the angular end edges 25^a of the extensions 64 and 65 as 30 in the form of my invention previously described. Slots or cut outs 68 are provided in the miter shaping guide so that the device may be moved close to the sewing machine needle.

From the foregoing it will be seen that I have 35 provided a simple yet efficient device for forming miter joints on fabric articles such as curtains, handkerchiefs, table cloths and the like, the use of which will save a great deal of time and insure a uniformity of such joints throughout the entire article or multiplicity of articles 40 being sewn.

Having described my invention what I claim as new and desire to secure by Letters Patent is:

1. A miter joint forming device for fabric articles, said device being adapted to be secured to a sewing machine and comprising a band folding and guiding outer shell, an inner shell having a mitered end, means for folding the band material about the said mitered end to form a miter joint on the band, said means comprising pivotally mounted fingers adapted to be swung into the interior of the inner shell at the mitered end thereof, and a slidably mounted rod upon which the said fingers are carried for withdrawing same from the interior of the inner shell after the miter joint is formed.

2. A miter joint forming device for fabric articles, said device being adapted to be secured to a sewing machine and comprising a band folding 60 and guiding outer shell, an inner shell slidably mounted in the outer shell for moving the said inner shell towards and away from the sewing machine needle, a mitered end on the said inner shell, and pivotally mounted means for folding 65 the band material about the mitered end to form a miter joint on the said band.

3. A miter joint forming device for fabric articles, said device being adapted to be secured to a sewing machine and comprising a band folding 70 and guiding outer shell, an inner shell slidably mounted in the outer shell for moving the said inner shell towards and away from the sewing machine needle, a mitered end on the said inner shell, pivotally mounted means for folding the 75

band material about the mitered end to form a miter joint on the said band, and a slidably mounted rod upon which the said means is carried as and for the purpose specified.

5 4. A miter joint forming device for fabric articles adapted to be secured to a sewing machine, said device comprising an outer shell substantially U shaped in cross section, an inner shell spaced from the outer shell forming a band folding and guiding U shaped channel between the walls of said shells, means at the ends of the U shaped channel for folding the edges of the band, a substantially U shaped shell slidably mounted between the walls of the first mentioned 10 inner shell, a mitered end on the said slidable shell, and pivotally mounted means for folding the band material about the mitered end to form a miter joint on the said band.

5 5. A miter joint forming device for fabric articles adapted to be secured to a sewing machine, said device comprising an outer shell substantially U shaped in cross section, an inner shell spaced from the outer shell forming a band folding and guiding U shaped channel between the walls of 15 said shells, means at the ends of the U shaped channel for folding the edges of the band, a substantially U shaped slidably mounted shell between the walls of the inner shell, a mitered end on the said slidable shell, pivotally mounted means 20 for folding the band material about the mitered end to form a miter joint on the said band, and a slidably mounted rod upon which the said pivotally mounted folding means is carried for the purpose specified.

25 6. A miter joint forming device for fabric articles, said device being adapted to be secured to a sewing machine and comprising a band folding and guiding outer shell, an inner shell having a mitered end, means for folding the band material about the said mitered end to form a miter joint on the band, said means comprising pivotally mounted fingers adapted to be swung into the interior of the inner shell at the mitered end 30

thereof, a slidably mounted rod upon which the said fingers are carried for withdrawing same from the interior of the inner shell after the miter joint is formed, and a spring for returning the fingers to normal position after being withdrawn from the joint. 5

7. A miter joint forming device for fabric articles, the said device being adapted to be secured to a sewing machine and comprising a lower shell section having a lower and upper wall 10 spaced from each other to form a channel substantially one-half of a U in cross section, an upper shell section formed similarly to the lower section and hingedly connected thereto, the upper wall of the lower section and the lower wall of 15 the upper section forming inner walls and extending beyond the end of their respective outer walls, a mitered end on each of the said inner walls, pivotally mounted means for folding the fabric material about the mitered end, slidable 20 means upon which the pivotal folding means is carried, and spring means for retracting the said slidable means after the material is folded about the mitered end.

25 8. A miter joint forming device for fabric articles, the said device being adapted to be secured to a sewing machine and comprising a lower shell section having a lower and upper wall spaced from each other to form a channel substantially 30 one-half of a U in cross section, an upper shell section formed similarly to the lower section and hingedly connected thereto, the upper wall of the lower section and the lower wall of the upper section forming inner walls and extending beyond the end of their respective outer walls, 35 means on the said extending walls for folding the edges of the fabric, a mitered end on each of the said inner walls, pivotally mounted means for folding the fabric material about the mitered end, and a slidably mounted rod upon which the 40 said pivotally mounted folding means is carried as and for the purpose specified.

DAVID H. ROSENBERG.
